(57) **CLAIM**

The ornamental design for a retractable hook for hanging wheels from a vehicle raised for service, as shown and described.

DESCRIPTION

FIG. 1 is a front, top, and left side perspective view of a retractable hook for hanging wheels from a vehicle raised for service showing my new design;

FIG. 2 is a front elevational view;

FIG. 3 is a left side elevational view;

FIG. 4 is a top plan view;

FIG. 5 is a right side elevational view;

FIG. 6 is a rear elevational view;

FIG. 7 is a bottom plan view; and,

FIG. 8 is a bottom perspective view, the broken lines showing a wheel hanging on the retractable hook are for illustrative purposes only and form no part of the claimed design.
